UNITED STATES PATENT OFFICE

ENOCH RECTOR, OF NEW YORK, N. Y., ASSIGNOR TO WAUKESHA MOTOR COMPANY, OF WAUKESHA, WISCONSIN, A CORPORATION OF WISCONSIN

INTERNAL COMBUSTION ENGINE

Application filed March 20, 1922. Serial No. 626,254.

The invention relates in general to an internal combustion engine and particularly relates to an improved form of head for such an engine when forming part of an engine of 5 the L-head type.

One objection to the operation of such engines now in general use is that the spark plugs, or other instrumentalities for firing the charge, become inoperative after they 10 have been in use for a while, due among other reasons to the fact that the spark plugs are heated by the fired or burned gases as they are ejected from the explosive chamber through the exhaust, during the scavenging 15 stroke of the piston.

Accordingly the primary object of the present invention is to provide a form of head for an internal combustion engine which will feature the positioning of the 20 spark plug out of the path of the hot fired gases as they are discharged and, on the contrary, the invention features the positioning of the spark plug in the path of the relatively cool incoming mixture or fuel 25 gases charge.

In this connection it is pointed out that the invention effects and uses stratification of the compressed charge, so that where it is to be ignited it may be sufficiently rich 30 for that purpose but gradually becomes leaner toward the other end of the charge, resulting in greater thermal efficiency for the type of engine referred to. This improved performance is further enhanced by 35 the passage and change of direction of the incoming combustible mixture over and at the hot exhaust valve, thus greatly assisting vaporization thereof.

An incidental object of the invention is to 40 provide a construction of head which will feature the injection of the incoming fuel gas charge tangentially into the piston cylinder.

Various other objects and advantages of 45 the invention will be in part obvious from an

inspection of the accompanying drawings and in part will be more fully set forth in the following particular description of one form of mechanism embodying my invention, and the invention also consists in certain new 50 and novel features of construction and combination of parts hereinafter set forth and claimed.

In the accompanying drawings

Figure 1 is a plan view looking down upon 55 the top of one of the cylinders of a multi-cylinder engine of the L-head type and illustrating in dotted lines an arrangement of fuel conducting parts constituting a preferred embodiment of the invention;

Figures 2 and 3 are each vertical transverse sectional views taken respectively on the lines 2—2 and 3—3 of Figure 1 looking in the directions indicated by the arrows.

There is shown in Figures 2 and 3 the upper portion of a water jacketed piston cylinder 10 having a piston bore 11 into the intake end of which gaseous fuel is admitted from the inlet port 12 and from which the hot fired gases are discharged through the exhaust 70 port 13, said ports being controlled respectively, by valves 14 and 15. The disclosure of the engine casing as thus far described is of conventional form and is illustrated to show the applicability of the invention to conventional structures. The top of the cylinder 10 is closed by a head 16 secured in place by bolts passing through the openings 17 and containing a water cooling space 18 all as is well known in the art of internal combustion 75 engines of the type under consideration.

The drawings also disclose a supplemental pressure actuated firing instrumentality 19 forming no part of the present disclosure and more particularly defined in my co-pending 80 application entitled Dual firing devices, filed under even date, Serial No. 625,255.

Referring to the novel head disclosed it is noted that its underside is recessed to provide a combustion space and elongated gas con-

ducting passageway 20, which passageway, as shown in dotted lines in Figure 1, is somewhat L-shaped in plan, that is it has a bend or turn in it, and discharges at its constricted end 21 into the bore 11 in position off-set from the axis of the bore. This construction causes the gases to enter the cylindrical bore 11 tangentially and downwardly into the bore as shown in plan by the dotted arrows in Figure 1. Considered in elevation the wall 22 defining the top of the passageway 20 is curved from its highest part adjacent the ports, downwardly to a maximum clearance above the bore 11, as more particularly shown in Figure 2. This causes the gases to sweep downwardly and spirally into the bore 11 as indicated by the dotted arrows in Figure 2.

It is a feature of this disclosure that the intake or inlet port 12 is positioned at the far end of the passage 20 remote from the cylinder so that the incoming gases must travel across the exhaust controlling valve 15, which is situated at the crotch of the L or bend of the passageway, as indicated by the dotted arrows in Figure 3, but the fired gases from the explosive chamber in the bore 11 pass directly out through the exhaust port 13 and are not caused to pass across the inlet controlling valve 14.

From this construction it is seen that the space 23 above the valve 14 in the passageway 20 is relatively cool and is not subjected to any material heating effect from the fired gases discharged through the exhaust port. A spark plug 24 of any approved form is positioned in this cooled space, preferably directly above the intake port.

By this construction it is seen that the spark plug is at all times removed from the path of the hot fired gases and deterioration of the same is minimized.

In operation it is to be understood that the engine functions as is usual in such constructions, the cold gases being admitted through the inlet port are compressed and fired all as is usual in internal combustion engine operation. The fired gases are discharged in their proper timed cycle of operation through the exhaust port, but at this time the valve 14 is closed as is usual and while there may, of course, be some slight heating of the spark plug, this will not be material for the fired gases in passing through the exhaust port are removed from any serious heating effect on the spark plug.

By this construction, also, the incoming mixture passing into and through the passageway 20 deposits particles of liquid fuel on the walls thereof, relatively many at the entrance and fewer and fewer toward the cylinder. On the compression stroke, the charge is compressed into the combustion space and, by the vaporization of deposited particles, a stratified charge results, that is a charge richest at the intake and spark plug

and leaning gradually toward the cylinder. Thus, by the present invention the known advantages attendant upon a stratified charge are gained in an L-head engine with a head of simple formation. Furthermore, the incoming mixture passes over the exhaust valve and, changing direction there, liquid particles are projected upon the hot exhaust valve and immediately surrounding surfaces, thus greatly assisting toward complete vaporization.

Having thus described my invention, I claim:

1. In an internal combustion engine, a cylinder, a piston in said cylinder, a combustion space comprising an elongated L-shaped passageway communicating at one end with said cylinder and having a valve controlled combustible gas inlet at its other end, spark ignition means disposed in said passageway with said combustible gas inlet at said other end, and a valve controlled burned gas outlet for said passageway positioned at the crotch thereof, said passageway being otherwise closed.

2. In an internal combustion engine, a cylinder, a piston in said cylinder, a combustion space comprising an elongated L-shaped passageway having one leg thereof lying tangent to and communicating at its end with said cylinder and having a valve controlled combustible gas inlet at its other end, spark ignition means disposed in said passageway with said combustible gas inlet at said other end, and a valve controlled burned gas outlet for said passageway positioned at the crotch thereof, said passageway being otherwise closed.

3. In an internal combustion engine, a cylinder and combustible gas inlet and burned gas outlet ports terminating side by side, a piston in said cylinder, a valve for each of said ports, a head overlying said cylinder and ports, said head having an elongated L-shaped combustion space and passageway formed in the under side thereof, said passageway having one end overlying said inlet port, its other end overlying a portion of said cylinder, and its crotch overlying said outlet port, and spark ignition means disposed in said passageway over said inlet port.

4. In a multiple-cylinder internal combustion engine, the combination with the cylinders having combustion spaces, of intake and exhaust valves appurtenant to each space and all in a line parallel to the longitudinal axis of the engine, and a wall between each intake valve and its combustion chamber to deflect the incoming mixture toward and over the exhaust valve.

5. In an internal combustion engine, a head structure for the cylinder formed with a shoulder constituting a deflecting wall whereby the incoming charge mixture is deflected toward and over the exhaust valve.

6. In an internal combustion engine the combination with the cylinder head of an L-shaped recess therein having its walls in contact with the engine cooling medium and at one end overlying and opening into the cylinder and intake and exhaust valves opening into said recess, the inlet valve being more remote from the cylinder whereby the incoming mixture is caused to flow over the exhaust valve.

7. In a multi-cylinder internal combustion engine the combination of a passageway pertaining to each cylinder, having its walls in contact with the engine cooling medium and opening at one end into the cylinder, an intake and exhaust valve opening into each passageway, the inlet valve being more remote from the cylinder than the exhaust valve, whereby the incoming mixture is caused to flow over the exhaust valve and all of said intake and exhaust valves being arranged parallel to and operated by a common cam shaft.

8. In a multi-cylinder internal combustion engine, the combination with a cylinder head having an L-shaped compression space pertaining to each cylinder, each of said spaces having one arm thereof overlying and opening into a cylinder and the other arm parallel to the engine cam shaft, of an intake and an exhaust valve opening into each of the latter arms and so located as to cause the incoming mixture to flow over the exhaust valve.

9. In an internal combustion engine including a cylinder block and a head secured thereon, the opposed faces of the block and the head being flat, a combustion chamber in the head having an arm overlying and opening into the cylinder, the inner end of the arm being disposed to direct the fuel mixture entering the cylinder outwardly of the cylinder against the wall thereof at the inner end of the arm.

10. In an internal combustion engine including a cylinder block and a head secured thereon, a compression chamber in the head having an arm overlying and opening into the cylinder, the inner end of the arm being disposed to direct the fuel charge entering the cylinder outwardly of the cylinder against the wall thereof substantially tangentially of the cylinder.

11. In an internal combustion engine, comprising a cylinder block and a head secured thereon, a compression chamber in the head having an arm overlying a portion of the cylinder and opening therewith, the inner end of the arm being bent outwardly to the cylinder wall.

12. In an internal combustion engine, comprising a cylinder block and a head secured thereon, a compression chamber in the head having an arm overlying a portion of the cylinder at one side thereof and opening

thereinto, the inner end portion of the arm being curved outwardly to the cylinder wall.

13. In an engine of the character described, a cylinder, a piston, a cylinder head having a primary valve controlled combustion chamber to one side of the cylinder, said cylinder head also having a secondary combustion chamber above a portion of the cylinder communicating with the primary chamber, said secondary chamber extending above a portion of the piston face to one side of the piston face center.

14. In an engine of the character described, a cylinder, a piston, a cylinder head having a primary valve controlled combustion chamber to one side of the cylinder and a secondary combustion chamber above a portion of the cylinder communicating with the primary chamber, said secondary chamber generally following the curvature of the piston face periphery.

15. In an engine of the character described, a cylinder, a piston, a cylinder head having a primary valve controlled combustion chamber to one side of the cylinder and a secondary combustion chamber communicating with the primary chamber and sloping downwardly therefrom and extending above the piston face at least to the plane of adjacent piston axes and remote from the piston face center.

16. In an engine of the character described, a cylinder, a piston, a cylinder head provided with a primary valve controlled combustion chamber to one side of the cylinder and provided with a secondary combustion chamber communicating with the primary chamber sloping downwardly therefrom above the piston face and curving about the axis of the piston.

17. In an engine of the character described, a cylinder, a piston, a cylinder head having a valve combustion chamber formed therein to one side of the cylinder and also having a secondary combustion chamber formed therein communicating with the valve combustion chamber, the volume of said secondary chamber being materially smaller than the volume of the valve combustion chamber, said secondary chamber extending above a portion of the piston face remote from the center of the piston face.

18. In an engine of the character described, a cylinder, a piston, a cylinder head having a valve combustion chamber formed therein to one side of the cylinder and also having a secondary combustion chamber formed therein communicating with the valve combustion chamber, the volume of said secondary chamber being materially smaller than the volume of the valve combustion chamber, said secondary chamber extending above a portion of the piston face adjacent the periphery of the cylinder.

19. In an engine of the character described, a cylinder, a piston, a cylinder head having a

primary valve controlled combustion chamber to one side of the cylinder and also having a secondary after-burning combustion chamber communicating with the primary chamber located above a relatively cool portion of the piston face.

Signed at New York city in the county of New York and State of New York this 1st day of March A. D. 1923.
